United States Patent Office

Des. 212,313
Patented Sept. 24, 1968

212,313

TYPEWRITER

Alfons Boothby, Wilhelmshaven, Germany, assignor to
Olympia Werke AG, Wilhelmshaven, Germany

Filed Feb. 1, 1968, Ser. No. 10,404

Claims priority, application Germany Sept. 7, 1967

Term of patent 14 years

(Cl. D64—11)

FIG. 1 is a perspective side view of a typewriter showing my new design;

FIG. 2 is a perspective rear view, and

FIG. 3 is a perspective front view of my new design.

The essential features of the design reside in the portions shown in full lines on the drawing, conventional keys and other details being shown in broken lines.

I claim:

The ornamental design for a typewriter, substantially as shown and described.
